CLAIM

The ornamental design for a plug protector, as shown and described.

DESCRIPTION

FIG. 1 is a front perspective view of a plug protector in accordance with another aspect of the present teachings.

FIG. 2 is a rear perspective view of the plug protector of FIG. 1.

FIG. 3 is a front view of the plug protector of FIG. 1.

FIG. 4 is a rear view of the plug protector of FIG. 1.

FIG. 5 is a top view of the plug protector of FIG. 1.

FIG. 6 is a bottom side view of the plug protector of FIG. 1.

FIG. 7 is a right side view of the plug protector of FIG. 1; and,

FIG. 8 is a left side view of the plug protector of FIG. 1. In the drawings, the broken lines illustrate portions of the plug protector that forms no part of the claimed design.
